UNITED STATES PATENT OFFICE.

HARRY DIAMOND, OF ROANOKE, VIRGINIA.

COMBINED CIGAR LIGHTER AND TIP CUTTER.

1,147,220.

Specification of Letters Patent.

Patented July 20, 1915.

Application filed February 23, 1915. Serial No. 10,014.

To all whom it may concern:

Be it known that I, HARRY DIAMOND, a citizen of the United States of America, and a resident of Roanoke, county of Roanoke, 5 State of Virginia, have invented certain new and useful Improvements in Combined Cigar Lighters and Tip Cutters, of which the following is a full and clear specification, reference being had to the accompanying 10 drawings, in which—

Figure 1 is a perspective view of a device embodying my invention; Fig. 2 a vertical longitudinal sectional view thereof; Fig. 3 a transverse vertical section on the line 3—3 15 of Fig. 2; Fig. 4 a horizontal section on the line 4—4 of Fig. 2; and Fig. 5 a detail sectional view partly in side elevation of the torch extinguisher.

The object of this invention is to provide 20 simple mechanism whereby the operation of the torch lighting sparker simultaneously actuates the tip cutter, and a further object is to so construct and arrange the filling 25 spout of the torch bowl or tank that it may be used as a handle for operating the sparker, as more fully hereinafter set forth.

In the drawings, *a* designates the tank or bowl of the torch, which is pivoted on a horizontal pivot at *b* to permit it to be 30 tilted forwardly and backwardly. The vertical wick-tube *c* of this tank extends upwardly through a slot in the upper part of a box *d* in which the tank is inclosed, and the tank is normally pulled backwardly by 35 a retractile spring *e*, this backward tilting action being arrested by contact of the wick-tube *c* with the rear end of the slot.

The tank is provided with a filling spout *f* which extends horizontally out through a 40 slot cut in the end wall of the box *d* in position where it may be conveniently used as a handle for swinging the torch forwardly in operating the sparker.

The sparking device is of any usual and 45 improved form; in the present instance I have shown it to consist of a piece of steel *g* fastened to the upper end of the wick-tube in such position that it will cause a spark when the torch is swung forwardly by co- 50 operation with the spring-actuated pivoted steel finger *h*. When the torch is in its

normal position, the upper inclined end of its wick-tube fits against a similarly inclined extinguisher *i* mounted on a suitable bracket fastened to the top of the box *d*. The usual 55 battery cell *j* and induction coil *k* together with suitable circuit wires are employed, the induction coil being conveniently mounted in the box *d* and the cell being conveniently housed in an adjustable case or box *l* at- 60 tached to the box *d*, the upper part of this adjustable case being provided with a removable glass cover *m* and a glazed front panel *n* and adapted to house a cigar box *o*. In the path of the wick-tube is mounted the 65 movable member *p* of a tip-cutter of usual form, so that when the wick-tube is moved forwardly it forces this cutter across the lower end of the tip-receiving cup *q* mounted on the top wall of the box *d* at a point 70 adjacent to the torch, where it will be convenient.

Having thus described my invention, what I claim is:

1. In combination, a casing, a movable 75 torch supported therein and having a wick-tube extending up through the top wall of said casing, means for lighting the torch when it is moved in one direction, and a tip-cutter on the under side of the top wall of 80 the casing having its movable member lying in the path of the movable torch, so that when said torch is moved on its lighting stroke the cutter will be operated directly by the torch. 85

2. In a cigar torch apparatus, the combination of a casing having a slot in its top wall and another slot in one of its side walls, a torch pivotally supported in said casing and having its wick-tube working through 90 the slot in the top wall, the tank of said torch being provided with a filling tube extending out through the slot in the side wall and serving as a handle by which the torch may be tilted, and means whereby the tilting 95 of the torch causes the wick to be lighted.

In testimony whereof I hereunto affix my signature in the presence of two witnesses.

HARRY DIAMOND.
